UNITED STATES PATENT OFFICE.

JOHN R. FREEMAN, OF PROVIDENCE, RHODE ISLAND.

APPARATUS AND METHOD OF CONSTRUCTING AND SINKING A CAISSON.

Application filed August 24, 1921. Serial No. 494,944.

This invention relates to an apparatus and method for constructing and sinking a caisson such as a hollow concrete supporting pier for a bridge or other purpose. The invention is particularly designed for use in connection with the construction and sinking of such a caisson or pier in silt or soft earth such as a river bottom but may be employed under any conditions where it is found advantageous.

One object of the invention is to provide an apparatus reacting against a loaded support surrounding the caisson for producing a downward thrust on the caisson periphery to assist in sinking it into the earth, thus expediting the work and assisting in the dredging action.

Another object of the invention is to provide an apparatus employing extensible suspending connections extending from a support surrounding the caisson to points on the periphery of the caisson and controlling the extension of these connections to insure a gradual and even sinking of the caisson into the earth, thus preventing any sudden drop of the caisson due to irregular conditions in the earth through which it is sunk and insure the gradual and even sinking of the caisson.

Another object of the invention is to provide means on the support surrounding the caisson and engaging the caisson periphery for centering and guiding the caisson as it sinks.

Another object of the invention is to combine two or more of the foregoing features in the apparatus so as to insure under the prevailing conditions the gradual, even and vertical sinking of the caisson.

These and other objects and features of the invention will appear more fully from the accompanying description and drawings and will be particularly pointed out in the claims.

The drawings represent simple and preferred forms of apparatus for carrying out the main feature of the invention in connection with the construction and sinking of a hollow concrete supporting pier designed to support a bridge from the bed of a river. The construction illustrated is particularly designed for use in comparatively soft earth such as alluvial soil or silt often forming to a great depth the bed of a river at its delta.

In the drawings:

Fig. 1 is a somewhat diagrammatic view

chiefly in vertical cross section taken transversely of the river bed, showing the pier sunk and one form of structure surrounding the pier and employed in sinking the pier.

Fig. 2 is a top plan view partially in horizontal cross section, showing a section of the surrounding structure and a section of the caisson being sunk.

Fig. 3 is a view chiefly in vertical cross section showing a section of the pier being sunk and surrounding structure and one of the extensible jacks.

Fig. 4 is a view chiefly in vertical cross section, showing a section of the pier ready to be sunk, the surrounding structure, and one of the extensible suspending connections.

Fig. 5 is a detail view, showing a means for extending the extensible suspending connections.

Fig. 6 is a somewhat diagrammatic view in vertical cross section, showing the pier in process of construction and partially sunk.

Fig. 7 is an enlarged detail, showing a shoe employed at the cutting edge of the pier and a portion of a reinforcing column and some of the other reinforcements of the pier.

Fig. 8 is a front elevation of a portion of the construction shown in Fig. 7.

Fig. 9 is a view in perspective of a portion of one of the columns of the pier.

In the embodiment of the invention herein illustrated where the pier is to be sunk in the bed of a river, a suitable coffer-dam and support or curb, surrounding the spot at which the pier is to be sunk, are first constructed.

The coffer-dam is constructed at a suitable distance around the pier site and to a height above the water level. In the form illustrated this coffer-dam is formed by driving piles 1 in concentric rows into the bed of the river and filling the space between the rows of piles with Chinese bundles of kaoliang 2, but any usual and suitable structure may be provided for this coffer-dam. After it is constructed it is gradually covered with a dike 3 of earth, the earth removed in the dredging operation during the sinking of the pier being utilized for that purpose. Stone rip-rap 4 may be employed where necessary to support and protect the coffer-dam and the dike as, for example, on the up-stream side. Immediately adjacent and surrounding the pier

site a row of interlocked sheet piling 5 is driven into the bed of the river. This also serves to form an inner wall for the material of the dike 3 to hold it back from the pier.

The surrounding support or curb is preferably a heavy timber framework construction supported on and tied into the bed of the river by the sheet piling 5 and by suitable piles 6 driven into the bed of the river. In the form illustrated this curb or support comprises the lower radially extending beams 7 secured to beams 8, carried by the sheet piling, and beams 9, carried by or supported on the piles 6. A suitable trussed framework is built up from the beam 7 and includes the vertical beams 10 adjacent the pier and the vertical beams 11 in a surrounding row. These beams carry the upper row 15 of radial transverse beams 12 tied together by the beams 13 at the front and 14 at the rear and braced transversely by the braces 15. The entire framework is firmly bolted together.

20 A suitable working platform 16 is provided on the beams 12 and surrounds the pier site.

25 A suitable trestle, formed by trusses 17 carried on the piles and other piles 18 and the curb already described, is constructed in any suitable manner and provides a track-way or platform 19 upon which the materials employed in the construction and sinking of the pier may be brought, stored and handled. This platform 19 may be extended entirely about the pier and be of such size and construction as is required under the particular conditions.

30 The pier is shown as constructed of reinforced concrete poured in successive layers above the ground and just prior to sinking. The earth is removed from the inside of the pier by suitable dredging or pumping operations in a familiar manner. The lower edge of the hollow pier or caisson is beveled 35 interiorly to provide a cutting edge at the exterior and the lower section of the pier is rigidly reinforced and provided with a steel cutting shoe which remains as a permanent portion of the pier. The pier is shown as 40 of generally circular or polygonal cross-section throughout that portion embedded in the earth. The portion of the pier above the earth, in the form illustrated, is tapered 45 inwardly at 20 at the sides so as to present a supporting section 21 extending lengthwise or up and down stream in the usual manner.

50 After the coffer-dam and timber curb or 55 supporting structure have been erected, the first or lowermost section of the pier or caisson is constructed upon and rests upon a temporary plank foundation 22, which is removed when the first section is ready for 60 sinking.

A steel shoe 23, forming the cutting edge, is bolted to a series of metal frames, shown in detail in Fig. 7. These frames each comprise the vertical angle-irons 24 and the inclined angle-irons 25 secured together by 70 the transverse plates 26. These frames are arranged radially and faced at the lower exterior with a metal plate 27 and the lower interior with metal plates 28 and 29, the cutting steel shoe 23 being bolted between 75 the plates 27 and 29. These frames form a strong reinforcement for the lower portion of the pier and also provide the forms for the concrete at the very lowermost section. The angle-irons 24 at their upper ends are 80 bolted to the flanges or rigid vertical columns 30, which preferably extend throughout the length of the pier and serve as vertical reinforcements for the pier and to receive and 85 transmit the forces of thrust and draft employed in connection with the sinking of the pier.

The forms employed in constructing the pier may be of any suitable construction. 90 As illustrated, the interior inclined surface above the plate 28 is completed by a wooden form 31. Otherwise the forms for the interior and exterior comprise suitable sectional metal plates 32, between which the concrete is poured, and which are removed after the 95 concrete is set and before sinking.

Suitable additional reinforcements may be provided as required for the concrete. Preferably, metal rods 33 are arranged concentrically in the lower beveled section and 100 held in place by resting on the plates 26. These give a very strong reinforcement to this section of the pier. Preferably also, the entire length of the pier is reinforced to the extent required in a similar manner 105 by similar rods 34, which may be supported upon angle-brackets 35 bolted to the interior of the columns 30. Other suitable reinforcement may be provided as required.

The wooden form 31 and the lowermost 110 interior forms 32 are provided with projections such as 36 to form depressions in the interior surface of the pier to interlock with the foundation plug, which is poured in place after the pier is sunk to its resting 115 place.

The number of triangular frames, such as shown in Fig. 7, and the number of vertical columns 30 employed will vary with the size of the pier, but in the construction 120 illustrated 16 are provided.

The columns 30, which are thus built into the concrete of the pier as it is formed, are an important feature. They are shown as 125 of the channel type of iron beam having the outwardly projecting flanges 37 and 38 and the back 39. The brackets or angle-irons 35, already referred to, are bolted to the back 39 and thus extend inwardly and are embedded in the concrete. The space be- 130

tween the flanges 37 and 38 is filled with concrete as these beams sink with the pier into the earth.

An important feature of the invention relates to the means and method employed for the forcing of the pier or caisson into the earth and the control of its sinking movement. The invention especially enables the pier to be constructed and sunk with great speed because the operations of dredging, sinking, form shifting and concrete pouring can go on simultaneously.

Heretofore it has been customary to load the caisson with heavy weights piled upon it or else to make the caisson itself excessively heavy in order to secure the necessary sinking force. Under these conditions the grab bucket of the dredger often removes the earth far below the cutting edge and then the caisson drops suddenly, not infrequently breaking or injuring the caisson or the surrounding working structure and injuring those employed. This irregular sinking movement of the caisson also permits the mud or soft earth to flow into the interior of the caisson, delaying the work and requiring an undue amount of pumping.

The present invention secures the steady and even sinking of the caisson into the earth as the earth is dredged out or removed from the interior. There is thus no sudden drop or movement of the caisson and little danger of a sudden inflow of mud or soft earth. Furthermore, the movement of the caisson is maintained evenly throughout its periphery, so that it sinks steadily and without tipping.

A simple and preferred form of apparatus by which the invention secures these results is illustrated and embodies two main features. First, a plurality of expansible jacks engaging and acting downwardly against the caisson periphery and engaging and reacting upwardly against the surrounding support; and second, a plurality of extensible suspending connections connected to the caisson periphery and to the support. Either or both of these are employed according to the varying conditions.

The forces exerted by these jacks and by these suspending connections are preferably applied to the caisson periphery through the medium of the vertical columns, so that the force, whether of thrust or draft, is transmitted through these columns to the comparatively hard set cement of the lower sections. This is an important feature because it prevents the caisson or pier from being cracked or broken apart as it descends, either under its own weight or under the thrusting forces, into the ground. Suitable means may be provided upon the vertical columns at frequent vertical intervals to be engaged by the jacks and extensible suspending connections. In the form illustrat-

ed a plurality of steps are provided at vertical intervals upon each vertical column. These are shown as heavy iron brackets securely bolted in place within the channel section of the vertical columns. The back 70 portion 40 of each bracket is bolted to the back plate 39 of the column and the side flanges 41 are bolted respectively to the side flanges 37 and 38 of the column. Each bracket presents a horizontal projection or 75 step 42, adapted on its top face to receive the end of the jack and on its lower face to be caught by a link or cross bar of the suspending connection. Preferably both of these devices will not act on the same step 80 at the same time, but if both are used at the same time, the jack will engage one step and the suspending connection another step on the same column.

The jacks may be of any suitable form 85 and the power for expanding them may be applied mechanically, by hydraulic pressure, by pneumatic pressure, or otherwise. So the number of jacks and the power exerted by each jack may be varied as the 90 conditions require. In the particular construction illustrated provision is made for sixteen powerful hydraulic jacks. As the particular construction of the jacks is not involved in this invention, it is sufficient 95 to illustrate them only in a general way. The jack comprises a hydraulic cylinder 43 and a piston or thrust bar 44. At its upper end the jack abuts against a heavy casting 45, fitting over the inner end of one 100 of the beams 12. The jack is supported by a frame 46, pivoted to the end of the beam, and is counterbalanced by a weight, which may be a tank 47 filled with sand, and connected by a rope or cable 48, running over 105 a pulley 49 with the jack. The curb or framework surrounding the caisson is suitably trussed or braced against the thrust of the jack. For this purpose tension rods 50 and 51 with suitable turn buckles 52 are 110 shown connecting the casting 45 to different points on the lower beam 7 of the curb or framework. When these jacks are used, the necessary weight against which the jack reacts is secured by loading the curb or frame- 115 work. This may be done by building a platform 53 on the beam 7 and a retaining wall 54 at the inner side and loading the frame with the earth, sand, or other material dredged out and forming part of the dike 3. 120 If this load is not sufficient, the curb may be built higher by means of additional beams 55, a platform 56 may be built on the beams 12, a retaining wall 57 may be built at the front and the load of earth or 125 wet sand carried up onto the platform 56.

A tremendous pressure, sufficient to overcome the resistance to sinking including the skin friction, may be furnished by the use of these jacks acting simultaneously through- 130

out the caisson periphery. The jacks may not be needed save during the latter portion of the sinking of the caisson or save upon meeting with some dense or particularly resistant character of earth, but they afford means by which under a wide variety of conditions the sinking of the caisson may be continued steadily and evenly, and they enable the caisson to be sunk as the dredging 10 at the interior progresses, so that there is no danger of the caisson holding back while the dredging proceeds and then the caisson falling with a jump and being broken or injuring the surrounding structure or the 15 men employed.

The feature of the extensible suspending connections may also be embodied in various forms. As illustrated, strong cable chains are provided, preferably one for each of the 20 vertical columns. These chains 58 are each provided at the lower ends with a connecting device or hook 59, having a cross bar 60, adapted to seat beneath the projections 42 of the steps. Each chain is connected to 25 suitable means mounted on the curb or surrounding framework, enabling it to be extended gradually under sure control. In the form illustrated a worm screw winch is provided for each chain, enabling it to be paid 30 out or extended an inch or two at a time and as slowly as desired. The chain 58 is shown as extended about the barrel 61 of the winch, carrying the worm wheel 62. This worm wheel engages a worm 63 on a vertical shaft 64, which may be turned in any suitable manner, as by hand. The winch is firmly seated on the curb or surrounding framework and each winch is shown as seated 35 on the inner ends of the beams 12.

40 These suspending connections are very desirable at the beginning of the sinking of the caisson. They act to maintain it in vertical position as it starts to sink and enable the sinking of the caisson to be controlled 45 so that there is no danger of any sudden drop or irregular tilting. The suspending connections may be employed during any portion of the sinking of the caisson or during the entire operation, if desired. If the 50 caisson in its sinking penetrates a pocket of soft quicksand or other similar material, these connections hold it against dropping or sudden injury to the surrounding structure or to the men employed.

55 The suspending connections may also be employed with the jacks being paid out gradually as the jacks expand to insure the even and steady movement of the caisson. By the use of these two devices, that is, the 60 expanding jacks and the extensible suspending connections, great rapidity of operation is secured under all conditions and all danger due to irregular or sudden movement of the caisson is prevented.

65 The caisson is preferably centered and

guided in its movement by means provided on the curb or surrounding framework. For this purpose suitable guide blocks 65 are placed on the vertical beams and suitable guide blocks 66 are secured to the inner 70 ends of the beam 7. The contacting faces of these blocks are greased in the same manner as the launching ways are greased for a ship. Thus, the caisson is centered and guided just prior to its entrance into the 75 earth.

Preferably also, means are provided for reducing the skin friction at the exterior of the caisson. For this purpose two features are provided. First, the exterior of 80 the caisson is formed with a very small upward taper. This taper is barely large enough to relieve the pressure of the surrounding earth and to admit the circulation of a thin film of water while sinking 85 and is not made sufficiently large enough to invite any extensive inward movement of the earth in which it is to be sunk. A taper of one per cent where the river bed is of silt or other similar formation, is found 90 to be about sufficient. Second, means are provided for supplying a thin film of water adjacent the cutting edge for lubrication. For this purpose a plurality of pipes 67 are built into the caisson as it is poured 95 and extend up vertically to the top. At their outer sides these pipes are bent horizontally around the caisson at a point a short distance above the cutting edge; and at their lower ends are provided with a plurality of openings 68 through which small jets of water are forced at the exterior periphery of the caisson. These pipes are 100 left in the caisson and form an additional permanent vertical reinforcement.

In the construction illustrated when the caisson, here shown in the form of a pier, is sunk to the desired depth, the bottom is closed by a permanent plug of concrete 69, poured in place by a tremie or bucket opening at the bottom. The concrete of this plug extends into and interlocks with the recesses provided by the projections on the lower forms in the main walls of the caisson. This plug is also preferably braced with 11 horizontal reinforcing bars 70 abutting against the interior periphery of the caisson walls.

The principles of construction involved in the pier as an article of manufacture are, 12 however, made the subject matter of another application.

Having thus described my invention, what I claim as new, and desire to secure by Letters Patent, is:

1. An apparatus for sinking a caisson vertically comprising a support on the earth surrounding the caisson, a plurality of expandable jacks engaging and acting downwardly against the caisson periphery and 13

engaging and reacting upwardly against the support, a load on the support of sufficient weight together with that of the support to take up the reaction of the jacks, 5 means for expanding the jacks gradually to force the caisson into the earth, and means carried by the support and engaging the caisson periphery for centering and guiding the caisson in its descent.

10 2. An apparatus for sinking a caisson vertically comprising a support on the earth surrounding the caisson, a plurality of extensible suspending connections connected to the caisson periphery and to the support, 15 and means for gradually extending said connections to insure the gradual descent of the caisson throughout its periphery.

20 3. An apparatus for sinking a caisson vertically comprising the elements defined in claim 2 together with means carried by the support and engaging the caisson periphery for centering and guiding the caisson in its descent.

25 4. An apparatus for sinking a caisson vertically comprising a support on the earth surrounding the caisson, a plurality of expansible jacks engaging and acting downwardly against the caisson periphery and engaging and reacting upwardly against the support, a load on the support of sufficient weight together with that of the support to take up the reaction of the jacks, a plurality of extensible suspending connections connected to the caisson periphery and the support, 30 means for gradually expanding said jacks, and means for gradually extending said connections, thus gradually to force the caisson into the earth and insure its even descent throughout its periphery.

35 40 5. An apparatus for sinking a caisson vertically comprising the elements defined in claim 4 together with means carried by the support and engaging the caisson periphery for centering and guiding the caisson in its descent.

45 6. An apparatus for sinking a caisson vertically comprising a support on the earth surrounding the caisson, and means carried by the support and engaging the caisson periphery for centering and guiding the caisson in its descent.

50 55 7. An apparatus for sinking a concrete caisson vertically comprising a plurality of rigid vertical columns built into the caisson periphery during its formation and vertically reinforcing and uniting the caisson, steps at vertical intervals on said columns, a support on the earth surrounding the caisson, a plurality of expansible jacks engaging 60 and acting downwardly against said steps and engaging and reacting upwardly against the support, a load on the support of sufficient weight together with that of the support to take up the reaction of the jacks, and 65 means for gradually expanding the jacks,

whereby the caisson is gradually and evenly forced into the earth and the thrust of the jacks is transmitted through the vertical columns to the lower hard set concrete of the caisson.

70 8. An apparatus for sinking a concrete caisson vertically comprising a plurality of rigid vertical columns built into the caisson periphery during its formation and vertically reinforcing and uniting the caisson, 75 steps at vertical intervals on said columns, a support on the earth surrounding the caisson, a plurality of extensible suspending connections connected to the steps and to the support, and means for gradually extending said connections to insure the gradual and even descent of the caisson throughout its periphery, the vertical columns acting to transmit the draft of the extensible connections to the lower hard set concrete of 80 the caisson.

85 9. An apparatus for sinking a concrete caisson vertically comprising a plurality of rigid vertical columns built into the caisson periphery during its formation and vertically reinforcing and uniting the caisson, 90 steps at vertical intervals on said columns, a support on the earth surrounding the caisson, a plurality of expansible jacks engaging and acting downwardly against said steps and engaging and reacting upwardly against the support, a load on the support of sufficient weight together with that of the support to take up the reaction of the jacks, a plurality of extensible suspending connections connected to the steps and to the support, and means for gradually expanding the jacks, and means for gradually extending the connections to insure the gradual 95 and even descent of the caisson throughout 100 its periphery.

105 10. The method of constructing and sinking a concrete caisson which consists in pouring successively horizontal sections of the caisson, building into the caisson as the sections are poured a plurality of rigid vertical columns, dredging the interior of the caisson, and applying a vertical downward thrust to said columns and therethrough past the relatively soft and fresh concrete to the 110 lower section of hard set concrete.

115 11. The method of constructing and sinking a concrete caisson which consists in pouring successively horizontal sections of the caisson, building into the caisson as the sections are poured a plurality of rigid vertical columns, dredging the interior of the caisson, and applying a suspending draft to said columns and therethrough past the relatively 120 soft and fresh concrete to the lower section 125 of hard set concrete.

In testimony whereof, I have signed my name to this specification.

JOHN R. FREEMAN.
